UNITED STATES PATENT OFFICE.

LELAND WILLIS AND OLIN F. WOODWORTH, OF GRENLOCH, NEW JERSEY, ASSIGNEES
TO BATEMAN MANUFACTURING COMPANY, OF GRENLOCH, NEW JERSEY, A CORPO-
RATION OF NEW JERSEY.

CULTIVATOR.

1,284,011.

Specification of Letters Patent.

Patented Nov. 5, 1918.

Application filed November 19, 1917. Serial No. 202,743.

To all whom it may concern:

Be it known that we, LELAND WILLIS and OLIN F. WOODWORTH, citizens of the United States, residing in Grenloch, New Jersey, 5 have invented certain Improvements in Cultivators, of which the following is a specification.

Our invention relates to that type of cultivator in which the cultivator blades are 10 mounted upon a frame comprising a center bar and opposite side bars, and our invention relates particularly to the construction of the slide for effecting the spreading apart or the drawing together of the side bars 15 of the frame, the object of our invention being to simplify and cheapen such construction as compared with the malleable iron construction heretofore used.

This object we attain in the manner here- 20 inafter set forth, reference being had to the accompanying drawings, in which—

Figure 1 is a top view of the bars of a cultivator frame of the type to which our invention relates and of mechanism in ac- 25 cordance with our invention for effecting the outward or inward swinging of the side bars of the frame;

Fig. 2 is a side elevation of certain of the members of said mechanism on a larger scale 30 than Fig. 1;

Figs. 3 and 4 are perspective views on an enlarged scale of the component parts of the slide whose movement effects the spreading apart or drawing together of the side 35 bars of the cultivator frame, and

Figs. 5 and 6 are perspective views of the blanks from which, respectively, the mem- bers shown in Figs. 3 and 4 are produced.

In Fig. 1 of the drawing, 1 represents the 40 central longitudinal bar and 2—2 the opposite side bars of a cultivator frame of the type to which our invention relates, these bars, in the complete machine, having cultivator blades mounted thereon in the usual 45 manner. The side bars 2 are, at their front ends, pivoted to a head 3 on the central bar 1, and said side bars are also provided with wings 4 which are connected by links 5 to a slide 7, the latter being mounted so as 50 to be free to slide forwardly and backwardly on the central bar 1 of the frame and having such movement imparted to it by a lever 8 pivoted to said central bar 1 and connected to the slide 7 by means of a link 9, as

shown in Fig. 2, the lever 8 being retained 55 in different positions of adjustment by engagement of a tooth on said lever with a rack 10 also mounted on the central bar 1 of the frame.

Heretofore in machines of this type the 60 slide 7 has been composed of a malleable iron casting, but such construction is expensive, and it is the object of our invention to provide a cheaper but acceptable substitute therefor.

On reference to Figs. 2, 3 and 4 of the drawing it will be noted that the slide 7 is composed of upper and lower members 23 and 24, shown, respectively, in Figs. 3 and 4, the member 23 being formed from the 70 blank shown in Fig. 5, and the member 24 from the blank shown in Fig. 6. The blank shown in Fig. 5 is a plate having a central opening 25, opposite members 26 at the ends of said opening and opposite mem- 75 bers 27 at the sides of the same, and the blank shown in Fig. 6 comprises a plate with opposite parallel end members 28, projecting side members 29, and a central mem- 80 ber 30, the latter being centrally connected to the end members 28 at 31 but being separated from said end members and from the side members 29 by incisions 32.

In producing the slide member 23 from the blank shown in Fig. 5 the central por- 85 tions of the end members 26 of the latter are bent upwardly above the plane of the side members 27, as shown at 33 in Fig. 3, and in producing the slide member 24 from the blank shown in Fig. 6 the end members 28 of the latter are bent upwardly on the lines y—y, Fig. 6, carrying with them the side members 29 and freeing the side por- 90 tions of the member 30 so as to form a mem- 95 ber 35 (Fig. 4) of U-shaped cross-section with central opening 36 in each side and horizontally projecting wings 37 at the bottom in line with said openings 36, these wings having in them openings 38 which, when the member 23 is slipped over the top of the member 24, will axially coincide with cor- 100 responding openings 39 formed in the side wings 27 of said top member, each pair of openings 38 and 39 receiving a bolt 40 where- 105 by the top and bottom members of the slide are held in proper engagement with the central bar 1 of the frame, said bolts 40 also serving as pivots for the inner ends of the

links 5 whereby the slide 7 is connected to the wings 4 on the side frames 2 of the cultivator.

The side portions 35 of the lower member 5 of the slide and the upwardly bent portions 33 of the top member thereof serve to provide side bearings for said slide on the bar 1 and thus prevent lateral movement of said slide in respect to said bar. When the ends 10 28 of the blank shown in Fig. 6 are bent upwardly as shown at 35 in Fig. 4 the side members 29 of said blank form upwardly projecting wings 41 (Fig. 4) with openings 42 for the reception of the pivot pin 43 for 15 the lower end of the link 9, whereby the slide is connected to the operating lever 8, as shown in Fig. 2.

The production of the slide 7 from sheets or plates of metal by punching and bending in the manner described materially cheapens these parts as compared with the cost of the malleable iron casting formerly employed, and the novel construction is quite as effective for the intended purpose and is 25 as strong as, or stronger than, the corresponding part as formerly made.

We therefore claim:

1. The within described slide for spreading and contracting the side bars of a cultivator frame, said slide consisting of upper and lower members, one embracing the upper and the other the lower portion of the central bar of the cultivator frame, and means for confining said upper and lower members in such engaging relation, said up-

per member consisting of a plate with central opening, laterally projecting side members and end members having portions bent into a plane above that of the side members.

2. The within described slide for spreading and contracting the side bars of a cultivator frame, said slide consisting of upper and lower members, one embracing the upper and the other the lower portion of the central bar of a cultivator frame, and means 40 for confining said upper and lower members in such engaging relation, said lower member consisting of a plate having upwardly bent side members with intermediate openings and horizontal base wings projecting 45 laterally beyond the side members in line with said openings.

3. The within described slide for spreading and contracting the side bars of a cultivator frame, said slide consisting of upper and lower members, one embracing the upper and the other the lower portion of the central bar of the cultivator frame, and means 50 for confining said upper and lower members in such engaging relation, said lower member consisting of a plate having upwardly bent side members with intermediate 55 openings, horizontal base wings projecting laterally beyond the side members in line with said openings, and upwardly projecting side wings above said openings.

In testimony whereof, we have signed our names to this specification.

LELAND WILLIS.

OLIN F. WOODWORTH.
